US0D1082712S

(12) **United States Design Patent** (10) **Patent No.:** **US D1,082,712 S**
(45) **Date of Patent:** **** Jul. 8, 2025**

(54) **CONTACT FOR CONNECTOR**

(71) Applicant: **Japan Aviation Electronics Industry, Limited**, Tokyo (JP)

(72) Inventor: **Kohei Ohara**, Tokyo (JP)

(73) Assignee: **Japan Aviation Electronics Industry, Limited**, Tokyo (JP)

(**) Term: **15 Years**

(21) Appl. No.: **29/924,290**

(22) Filed: **Jan. 18, 2024**

(30) **Foreign Application Priority Data**

Aug. 2, 2023 (JP) ..... 2023-015815 D

(51) **LOC (15) Cl.** **13-03**

(52) **U.S. Cl.**

(57) **CLAIM**

The ornamental design for a contact for connector as shown and described.

DESCRIPTION

FIG. 1 is a front elevational view of a contact for connector showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof; and,

FIG. 10 is a rear, left, and top side perspective view thereof.

1 Claim, 9 Drawing Sheets
